5 Claims. (Cl. 209—111)

The invention relates to a preadjustable control system for selecting, according to characteristics or numerical values, vouchers and the like as they are fed past a sensing device. For comparing preset values with sensed values or characteristics, the sensed values pass into a comparison mechanism in the form of electric, optic, acoustic or magnetic impulses.

In the case of setting devices of sorting machines or similar comparing apparatus it is known to effect the sorting operation for only one place of the index value at each passage through the setting device so that, for example, for a 10-place characteristic the sorting is completed only after the tenth pass. The known arrangements are also open to the objection that a group selection of a plurality of characteristics of one place can be carried out only after several passes for one sorting compartment or, in the case of one pass, distributed to several sorting compartments. Although the passes take place at a high speed, the actual time occupied for sorting is dependent upon numerous manipulations for each fresh run, for example, fresh setting of the desired next following place index number, introducing and removing the vouchers.

An object of the invention is to provide an apparatus for comparing set characteristics with automatically sensed single or multiplace index values, which can be connected up in front of known accounting, calculating and sorting machines so that on the passage of a voucher or a punched hole card through the apparatus the characteristics are sensed and compared with the preset index values; when the index values are in agreement, the bookings can be carried out and, after running off, the vouchers can be guided to the desired sorting compartment. The comparison apparatus also allows a group selection of several index values of one place as the vouchers pass through the apparatus once.

The comparison mechanism operates substantially by voltage stabilization which is embodied by electric elements corresponding to the maximum number of places of the characteristic. This electric stability is upset by keys corresponding to the desired index values and re-established by sensed impulses produced by stepping mechanism or other sequence elements, so that, in the case of conformity, other functions, such as booking or counting and sorting can take place.

The invention consists substantially in that all comparison mechanisms are connected to a single control element for each index value place influenced by the sensing mechanism, and adjustable groups of setting members, a bridge connection and a switching element, are co-ordinated to the comparison mechanisms and, in the case of conformity between the preset index value and the sensed value, switch in the evaluation arrangements.

It is also within the scope of the invention to count and sort such articles as merchandise, letters, cheques and the like passing the sensing mechanism. In the case of counting, when a preset number is reached the next counting operation can be introduced. Each quantity of articles counted can be passed on for further treatment, for example for packing. Several counting operations independent of each other can be carried out simultaneously on a single conveyor.

5 10 A preferred embodiment of the invention is illustrated by way of example in the accompanying drawings.

In these drawings:

Fig. 1 is a block diagram of a preadjustable control system with sensing device, and

15 Fig. 2 is a wiring diagram of the preadjustable control system.

For the purpose of explaining the invention, the sensing and comparison of a voucher is shown diagrammatically by way of example. Between a source of light

20 20 and a number of light sensitive sensing heads 21¹—21ⁿ, such as photoelectric cells, photomultiplier tubes, or other well-known radiation sensitive elements, a passage for perforated vouchers 30 is arranged. Connected to each of the sensing heads 21¹—21ⁿ is, if necessary, an impulse

25 amplifier of a group of amplifiers 22¹—22ⁿ and a stepping mechanism, such as a telephone type stepping relay, of a group of stepping mechanisms 23¹—23ⁿ, each with two contact paths 24 and 35, the contact path 24 serving to indicate the sensed characteristic or numerical value

30 30 and the contact path 35 for zero control. As shown in our Patent 2,831,633 as relays R1-A to R1-D, switch contacts 41¹—41ⁿ, controlled by relay coil 40, are inserted in the transmission path between the amplifiers 22 and the stepping mechanisms 23. The number of the sensing heads 21¹—21ⁿ with associated switching means is dependent upon the number of numerical places of the sensed value of a line. Leads connect each contact of

35 35 the contact paths 24¹—24ⁿ to setting members 25¹—25ⁿ of individual comparison mechanisms 26¹—26ⁿ, which compare the value set by hand or mechanically with the sensed value of the characteristic. Each of the comparison mechanisms 26¹—26ⁿ comprises the setting members

40 40 25¹—25ⁿ, 25¹—25ⁿ or 25¹—25ⁿ, respectively, and one of relays 27¹—27ⁿ. The switch over mechanisms, when the sensed characteristic corresponds with the set index

45 45 value, pass on the following sensing of the calculation value to one of associated calculating mechanisms 28¹—28ⁿ and actuate one of sorting flaps 29¹—29ⁿ. Any number of comparison mechanisms 26¹—26ⁿ can be connected in parallel with this comparison mechanism

50 50 26¹, the number being preferably determined by the desired number of possibilities of evaluating a voucher 30 passing through the apparatus. A zeroizing apparatus 31, similar to that illustrated in Figs. 8, 9 and 10 of our Patent 2,831,633, and described in column 20 of that patent, is provided for zeroizing the stepping mechanisms

55 55 23¹—23ⁿ.

The control system operates in the following manner:

60 60 The setting members 25¹—25ⁿ of the individual comparison mechanisms 26¹—26ⁿ are set to the desired index values before the vouchers 30 pass through the machine. When the voucher arrives under the slide contact Sch 1, the relay R2 releases and applies current to the sensing

65 65 heads 21¹—21ⁿ via its contact 3 and the contact of the relay LR-1. As a voucher with its index values runs past the sensing device, all the index values are sensed by the sensing heads 21¹—21ⁿ either simultaneously or successively. The impulses resulting therefrom are transmitted via the amplifiers 22¹—22ⁿ to the stepping mechanisms 23¹—23ⁿ which step their sliders on to a contact of

70 70 the contact paths 24¹—24ⁿ corresponding to the number

of impulses. The contact path 24 receives, through the stepping mechanism 23, as many impulses as the sensing head 21 transmits, and, thus, the slider of the contact path 24 turns by a corresponding number of steps; the same applies to the contact arm for the zero control 35, in a manner similar to that disclosed in Figs. 8, 9 and 10 of our Patent 2,831,633. When the impulses received from the voucher correspond with the values preset in the setting members 25¹—25ⁿ, the relays 27¹—27ⁿ are energized by means of the contacts 16 of the relays 34 and the leads 17¹—17ⁿ. After the sensing of the characteristics of the voucher has been accomplished and by opening the contact K3 the relay R4 releases and energizes the relay 40 via its contact 1. This relay switches over its contact 41¹—41ⁿ and interrupts the connection from the connected amplifiers 22¹—22ⁿ to the stepping mechanisms 23¹—23ⁿ and establishes a connection from the amplifiers 22¹—22ⁿ to the contacts of the leads 28¹—28ⁿ. The relays 27¹—27ⁿ, corresponding to relays LRZ1 to LRZ4 of Patent 2,831,633, transmit further impulses of the sensed calculation values of the voucher to the calculating mechanism co-ordinated thereto. At the same time the control of a sorting flap 29¹—29ⁿ in a separate sorting mechanism is initiated by the switch-over mechanism 27¹—27ⁿ. After the sensing of the vouchers has taken place, the stepping mechanisms 23¹—23ⁿ are returned into their initial position by the zeroizing mechanism 31. Therein the relay LR-I is operated. Upon operation this relay switches off the sensing heads 21¹—21ⁿ by opening the contact 1. The relay LR-I holds itself via its contact 2 and the contact of the relay RO-I until the selectors 23¹—23ⁿ have arrived at their initial positions. When all the stepping mechanisms have reached their initial position, the contact paths 35¹—35ⁿ of the stepping mechanisms 23¹—23ⁿ are cleared via their cut-through circuit for the sensing of the following voucher. The contact banks 35 serve the purpose of checking whether the stepping mechanisms 23 are in their zero positions at the beginning of a sensing operation. This arrangement is quite usual in the telecommunication art. In Fig. 1 the selectors 23 are shown in their normal position, so that the contact banks 35¹—35ⁿ associated with the respective selectors 23 establish a connection from the left-hand side of the drawing, which is ground, through the relay at the right and to the positive terminal of a source of electrical energy (not shown). The relay is adapted to switch-in the sensing heads 21, when the selectors 23 are in their zero position.

Fig. 2 shows setting members 32¹—32ⁿ of a comparison mechanism 26¹ cooperating with the contact paths 24¹—24ⁿ and a tube amplifier 33 with a relay 34 coupled to all the setting members 32¹—32ⁿ of a comparison mechanism. Leads 11 connect the contact paths 24¹—24ⁿ to groups of setting members 32¹—32ⁿ of the individual setting mechanisms. The contacts 0 to 9 of the group of setting members are united and connected with a switch 12 which, on the setting of the index value place into position 1, is switched on to the groups of setting members.

Each switch 12 has a contact 13 connected through a resistor 14 and a wire 15 to a two stage amplifier 33. The amplifier has its output connected to the relay 34 for operating the relay contacts 16 which serve to apply a source of electrical energy through line 17 to the switch-over mechanisms 27 to prepare them for the reception of the calculating values and sorting instructions.

The operation of the setting members 32¹—32ⁿ is based on a bridge connection between the connected up resistors 14 and a load resistor 18 of the tube amplifier 33.

In the example illustrated in Fig. 2 the index value 2 is set in the group of setting members 32¹ and the index values 3, 4 and 5 in the group of setting members 32². No index value has been introduced in the group of setting members 32ⁿ, so that the switch cuts off the

group 32ⁿ with its switch-over contact 13 and thereby switches the bridge arm belonging thereto into balance over the position 2.

If the voucher has, for example, the index value "23" the slider of the contact path 24¹ runs on to the contact "2" and the slider of the contact path 24² on to the contact "3." Thus all resistors 14 are under current so that the bridge of the resistors 14 to the loading resistor 18 of the tube amplifier 33 is in balanced state and the relay 34 responds. The through-switching in the case of index values "24" and "25," takes place in a similar manner. In the case of all other index values at least one resistor 14 receives no current, and the balance of the bridge to the loading resistor 18 is upset.

From this example it can be seen that both the index values with more than one place and also entire groups of index values can be evaluated during a single passage of the vouchers.

If additional comparison mechanisms are connected up these can operate in the same columns in the manner above described, but with different index values, or in different index value columns.

From the above detailed description of the invention, it is believed that the construction will at once be apparent, and while there is herein shown and described a preferred embodiment of the invention, it is nevertheless to be understood that minor changes may be made therein without departing from the spirit and scope of the invention as claimed.

30 We claim:

1. A preadjustable control system for selecting, according to characteristics or numerical values, vouchers and the like as they are fed past the system, comprising in combination a sensing mechanism for sensing information recorded on information bearing members supplied to the system; a control element influenced by the output signals from said sensing mechanism; a comparison mechanism for each order in which information is recorded on said information bearing member connected to said control element; each of said comparison mechanisms comprising adjustable setting members, a bridge connected to said setting members, a switching element operated by said respective control element and adapted to generate a signal when a preset index value determined by the operation of said setting members corresponds with a sensed index value determined by the operation of said switching element.

2. A control system as set forth in claim 1, wherein each group of setting members has a reversing switch 50 for switching in the bridge connection and maintaining a bridge arm in balanced state in the case of a group of setting members being unused.

3. The control system defined in claim 1 wherein said setting members are arranged in parallel to be sequentially connected to said switching element whereby a plurality of comparisons may be achieved by each comparison mechanism.

4. A control system for generating control signals upon the detection of correspondence between preset values and sensed values, said system comprising sensing means for sensing information recorded upon an information bearing member, said sensing means having individual sensing elements for each order in which information is recorded on said members; a plurality of stepping 60 switches each comprising a control coil connected to individual sensing elements for receiving information therefrom, a movable contact arm under the control of said control coil, and a plurality of stationary contacts arranged to be sequentially connected to said movable contact arm; a plurality of settable setting members each connected to an individual stationary contact of a stepping switch; said settable setting members being adapted to pass signals when set and adapted to inhibit the passage of signals when not set; signal responsive means 65 connected to the setting members of any order for re-

ceiving a signal indicating the correspondence of a settable value as determined by the setting of the settable members and of a sensed value as determined by the operation of the movable contact arm; and means for supplying energy to said movable contact arm for passage through said stationary contacts and said setting members to said signal responsive means.

5. The control system defined in claim 4 further including means for returning the movable arms to a rest position upon the completion of a comparison cycle.
